UNITED STATES PATENT OFFICE

ARTHUR HENRY COOPER, OF IVER, ENGLAND, ASSIGNOR TO VICTOR TALKING MACHINE COMPANY, A CORPORATION OF NEW JERSEY

ELECTROMAGNETIC COUPLING DEVICE

Application filed February 5, 1931, Serial No. 513,759, and in Great Britain February 4, 1930.

The present invention relates to electromagnetic coupling devices, such for example, as are used in radio receivers. More particularly, it relates to coupling means of the above type for use between the high or radio frequency circuits of receiving apparatus and the like.

In a radio receiver employing electromagnetically coupled circuits, the volume of sound emitted by a loudspeaker or similar device in the output circuit of the receiver can be controlled by varying the coupling between the circuits. This is usually done by moving an inductance coil in one of the circuits with respect to a corresponding inductance coil in the other circuit. It is found, however, that as the moving coil is shifted from the position of zero coupling the energy transferred increases very rapidly at first and more slowly afterwards. In order to obtain an apparently uniform increase in the output energy, judged audibly, it is necessary that this transfer of energy between the coupling coils should increase slowly at first, and more rapidly afterwards.

It is an object of the present invention to provide means whereby this slow initial transfer of energy between the coupling coils can be attained.

According to the present invention an electromagnetic coupling device has associated therewith a low resistance short-circuited coil or shield which is arranged to have maximum magnetic coupling with the moving coil of the device when the said moving coil is near the position corresponding to zero coupling between the coils of the device.

The invention will be described by way of example with reference to the accompanying drawings, in which Fig. 1 shows an electromagnetic coupling device of the so-called variometer type, in which the moving coil is mounted within a cylindrical fixed coil and is rotatable about an axis which is at right angles both to its own axis of symmetry and the axis of symmetry of the fixed coil, while Fig. 2 shows the invention applied to an alternative form of device.

Referring to Fig. 1, a moving or rotatable coil 1 which may form part of a circuit car-

rying energy to be transferred, is arranged to rotate inside of a conducting cylinder or shield ring 2 open at both ends, the cylinder being fixed as shown in such a position that its axis of symmetry will coincide with the axis of symmetry of the moving coil 1 when the latter is in a position corresponding to zero coupling between the coil 1 and a fixed coupling coil or winding 4. This position is substantially at a right angle to the fixed coil 60 or winding 4. The cylinder is suitably perforated to allow the passage through it of the spindle 3 carrying the moving coil. The annular shield member 2 provides a closed loop which links electromagnetically with the moving coil in such a way as to be effectively a short-circuited turn at the neighborhood of zero coupling of the coils and by this means the zero is spread out and the increase of energy transferred from the moving coil to 70 the fixed coil 4 is rendered more gradual in the neighborhood of the zero position.

In Fig. 2 is shown the invention as applied to an electromagnetic coupling device of the type in which a moving coil 11 is adapted to swing about an axis 12 so that the angle between the planes of coil 11 and a fixed coil or winding 10 can be varied. In this case the shield 13 in the form of a copper ring is situated with its plane at a right angle to the plane of the fixed coil 10 and in such a position that it lies in the plane of and surrounds the moving coil 11 when the latter is in the position corresponding to zero coupling between the coils of the device.

The invention is not limited to electromagnetic coupling devices of the type described above but may be applied to any such device in which the amount of coupling is variable by relative movement between the coupling coils constituting the device.

Having now particularly described and ascertained the nature of my said invention, and in what manner the same is to be performed, I declare that what I claim is:

1. An electromagnetic coupling device comprising a fixed coil, a second coil movable with respect to the fixed coil to a position of zero coupling, and a low-resistance short-circuited shield ring arranged to surround

and provide maximum magnetic coupling with the moving coil when the said moving coil is near the position corresponding to zero coupling between the moving and the fixed coils of the device.

5 2. An electromagnetic coupling device including a movable coil, a cylindrical fixed coil, said movable coil being rotatable about an axis which is at right angles both to its 10 own axis of symmetry and to the axis of symmetry of the fixed coil, and a conducting annular shield interposed between said coils, said shield being mounted so that its axis of symmetry is substantially at right angles 15 both to the axis of rotation of the movable coil and the axis of symmetry of the fixed coil.

3. An electromagnetic coupling device including two angularly displaced coils, one of 20 said coils being movable to swing about an axis such that the angle between the two coils is variable to provide a coupling range including zero coupling, a conducting shield ring arranged to lie in the plane of and surrounding the moving coil when the latter is 25 in a position corresponding to substantially zero coupling between the coils of the device.

4. A high frequency circuit coupling device including in combination, a pair of electromagnetically coupled coils, a conducting shield interposed between said coils, and means for moving one of said coils with respect to the shield and the other coil to vary 30 the coupling between said coils in a predetermined manner.

5. The combination, in a high frequency circuit coupling device, of a pair of electrically coupled windings, means for moving one of said windings to a position coaxial 40 with the other and to another position at an angle thereto, and conducting means arranged to provide a short-circuited ring shield about said movable winding when in said last named position.

45 In testimony whereof, I have hereunto subscribed my name this twentieth day of January, 1931.

ARTHUR HENRY COOPER.
